UNITED STATES PATENT OFFICE.

JOHN C. FISCHER AND JOHN A. FISCHER, OF LEXINGTON, OKLAHOMA.

LANDSIDE FOR PLOWS.

No. 906,401.

Specification of Letters Patent.

Patented Dec. 8, 1908.

Application filed June 16, 1908. Serial No. 438,842.

To all whom it may concern:

Be it known that we, JOHN C. FISCHER and JOHN A. FISCHER, citizens of the United States, residing at Lexington, in the county 5 of Cleveland, and State of Oklahoma, have invented a new and useful Landside for Plows; and we do hereby declare the following to be a full, clear, and exact description of the invention, such as will enable others 10 skilled in the art to which it appertains to make and use the same.

This invention pertains to a plow and particularly to the special construction of such device; the invention in its fundamental 15 principles resides in improved constructions, for instance, a removable elongated bar, which is slightly adjustable with relation to and longitudinally of a plow, which elongated bar when in position, as shown in Figure 1 of 20 the drawings, is held substantially and rigidly in position, that is, laterally of the plow, as will be readily manifest.

The invention aims as a further object to dispose the said elongated bar upon an inclination, so that the plow point and mold 25 board of the plow may be inserted slightly further than would otherwise be the case, through the medium of the slight longitudinal movement of said elongated bar.

30 This invention comprises further objects and combinations of elements, which will be hereinafter more fully described, shown in the accompanying drawings, and the novel features thereof will be pointed out by the 35 appended claim.

The features, elements and the arrangement thereof, which constitute the above entitled invention, may be changed and varied, that is to say, in an actual reduction 40 to practice, with the understanding that the changes and variations accruing from said reduction to practice are limited to the scope of the appended claim.

To obtain a full and correct understanding 45 of the details of construction, combinations of features, elements and advantages, reference is to be had to the hereinafter set forth description and the accompanying drawings in connection therewith, wherein—

50 Fig. 1 is a side elevation of a portion of a plow, showing the improved features thereof. Fig. 2 is a sectional view on line 2—2 of Fig. 1, showing the manner in which the elongated removable bar is held. Fig. 3 is a perspective 55 view of the member of the plow for holding

the elongated bar. Fig. 4 is a detail perspective view of the said elongated bar.

In regard to the drawings, wherein similar reference characters indicate corresponding parts in the several illustrations, by figures, 60 1 designates a portion of a plow, which is provided with an angled portion 2, as shown in Fig. 3 of the drawings, which angled portion projects upon the land side of said plow, and its upper surface, as seen in Fig. 1, is inclined, as at 3, so as to cause the elongated bar 4 to be disposed upon an inclination, reference being had to Fig. 1 of the drawings. 65

Projecting upwardly from the portion 2, and from the inclined face thereof, are a pair 70 of studs or lugs 5, which are provided with apertures 6, which are in registration with the apertures 7 of the plurality 8, provided in the vertical portion of the plow 1, as seen clearly in Fig. 3 of the drawings. 75

Held securely and rigidly, that is, transversely of the plow, is the elongated bar 4, which is disposed between the studs, lugs or projections 5 and the vertical portion of the plow, and is securely held in such position by 80 the bolts and nuts 9 and 10, as seen clearly in Figs. 1 and 2 of the drawings. Preferably, in utilizing and disposing of the bar, the edges 11 and 12 of the mold board and the vertical portion of the plow are designed to 85 be disposed flush with one another, but, if it is so desired, that is, in practice, the said bar 4 may be disposed in a different position, forward or rearward of the edge 12 of the vertical portion of the plow, thereby dispos- 90 ing the said edges out of correlation or alinement. The different positions of the bar 4 may be obtained by re-registering the various apertures 13 of said bar and the apertures 7 and 8 of the vertical portion of the plow, 95 after which reinserting the said bolts 9, as will be clearly and readily manifest.

The portion 1 of the plow is provided with apertures 14, by which downward projections (not shown) may be connected by any 100 suitable means, to the portion of the plow 1; these downward projections, just referred to and not shown in the drawings, project from a plow beam, (not shown), in the usual manner. To the forward end of the said elongated bar the plow point 15 and the mold board 16 are securely fastened, by means of screws or bolts, as seen at 17, the bolt 17 assists in securely holding a bar 18 to the land side of said elongated bar, and to which bar 110

18 the mold board is securely fastened, by means of bolts 19, as seen clearly in Fig. 2 of the drawings.

From the foregoing, the essential features, elements and the operation of the device, together with the simplicity thereof, will be clearly apparent.

Having thus fully described the invention, what is claimed as new and useful, by the

10 protection of Letters Patent, is:—

A plow comprising a solid one piece angular member, said angular member comprising a vertically, disposed, elongated portion, a lateral projecting portion, said lateral projecting portion being of tapering contour and provided with integral upwardly projecting studs; a bar having a mold board and a plow point, said bar being secured between said

studs and the said vertically disposed elongated portion and disposed upon an inclination by contact with said lateral projecting portion, said bar being detachable and is designed to be disposed in various positions correlative with said member, and means for securing said bar in various positions between said studs and said vertical portion, as specified.

In testimony whereof we have signed our names to this specification in the presence of two subscribing witnesses.

JOHN C. FISCHER.
